T. W. JOHNSON

BRIEF CASE OR BAG

Filed Aug. 4, 1927

UNITED STATES PATENT OFFICE.

TITIAN W. JOHNSON, OF POTOMAC BEACH, VIRGINIA.

BRIEF CASE OR BAG.

Application filed August 4, 1927. Serial No. 210,587.

This invention relates to improvements in brief bags.

The objects of the invention are generally those as set forth in my copending application, Serial No. 174,855, filed March 12, 1927, that is to say, briefly to provide a brief bag or case characterized in that it has permanently attached thereto, and forming a part thereof, an apparel section to which access 10 may be gained independently of access to the papers section of the bag.

However, an additional object of the present invention is to so construct the case that it may conserve all of the outward appearances 15 of an ordinary brief bag, there being nothing, without the closest inspection, to indicate otherwise. A still further purpose is to so construct the bag that the fly or flap adapted more particularly, in the present instance, to 20 cover and conceal and close the papers section, will also envelope the upper edge of the apparel section, when said flap is closed, but will in no way interfere with the independent opening and closing of the apparel section.

25 As a result of this arrangement of the flap it becomes unnecessary to employ more than one lock on the case, and that will preferably be a lock of the kind commonly employed to lock the flap or fly to the front of the papers section. The position and use of a lock of this character is so well known that it has not been illustrated in the present instance. As will appear the apparel section may be 30 held closed by the ordinary hinge fasteners 35 which need not be disturbed when opening the brief bag to gain access to the papers section.

From the following will at once appear a 40 number of details of construction wherein the present bag differs from that illustrated in my copending application above referred to.

In the drawings:

Figure 1 is a perspective view of the case.

Figure 2 is a similar view, showing the case 45 open.

Figure 3 is a vertical section taken about on line 3—3 of Figure 1, the handle or grip being omitted.

Figure 4 is a detail section showing another 50 manner of forming the box-like section. This corresponds to the construction shown in copending application hereinbefore referred to.

Referring to the drawings:

The numeral 1 designates the case as a 55 whole; 2, the expandable papers sections, and 3, the apparel section. The papers section may, for the most part be made up in the usual way, that is to say, with a front wall 4, intermediate partitions 5, forming pockets, but the 60 rear wall 6, of the last pocket of the apparel section is preferably formed of stiffer or more rigid material and provided with a peripheral substantially L-shaped flange 7, with which the part 6 and the cover therefor, forms 65 a box-like member, including a cover 9 hinged to the lower flange 7, by hinges 8, the cover being adapted to fold flatwise against the other portion of said box-like member to form a closure. The upper edge of the apparel section, with parts carried by the upper flange 7, and the cover 9, is provided with cooperating 70 fastening devices *a*, which can not be reached for opening the apparel section until the paper section is opened, as will appear. 75

The back part of the bottom, and part of the front of the case is enveloped in a leather envelope 10. The lower end of this envelope is brought under the edge of the apparel section and up between the bottom of said section and the last pocket of the papers section, as indicated by the numeral 11, where it may be secured by any suitable means. This envelope terminates at its upper end in a flap or fly 12, which may be held in place by, as before intimated, a suitable lock, in addition to straps 13, which may extend as shown, entirely around the case or bag, as is common in ordinary brief bags. The back of the bag is provided with keepers 14, which are preferably stitched by stitches *b*, to the back or envelope 10, and this stitching, as indicated had better extend entirely through the cover section and serve as the means for uniting the envelope and said section. 90

95 It will be noted that the rear wall of the last pocket of the apparel section gives to the last pocket of the papers section such rigidity as to well adapt it for carrying drawings, photographs and other flat objects that may 100 be liable to injury, did not this last pocket have the characteristics mentioned.

The front of the fly or flap is provided with usual keepers 15, for the straps 13, which co-operate with the usual buckles 16. 105

It will be seen from the foregoing that the

apparel section is almost completely concealed by the envelope 10, thus giving to the brief bag the appearance of an ordinary bag. Indeed, should it be found desirable, the ends 5 of the apparel section need not extend flush with the end edges of the envelope 10, and the apparel section be dropped back at both ends, to further conceal the apparel section.

Obviously, to gain access to the papers section it is only necessary to throw the flap back, and the flap being integral with and forming a part of the envelope 10, need only be carried back to the extent permitted by the stitches which secure the top keepers 14, to 10 the lid or cover of the apparel section. The fastening devices *a* however, are of such character that they must be manually lifted or deliberately opened, consequently the movement of the fly or flap to expose the 15 papers in the papers section will not, as intimated, open the apparel section. However, when these fastenings are manipulated for opening purposes the lid of the apparel section may be readily opened, turning on its 20 hinges 8. Indeed, the hinges 8, may be dispensed with and the part 17 of the envelope may serve as a hinge. However, I believe the hinges to be preferable because they serve as means for definitely locating the lid or 25 cover relative to the box-like section, thus aiding in the opening and closing of said section.

In manufacture the rear wall of the papers section, which is at the same time the bottom 30 of the apparel section, may be made of any suitable material, as also may be the cover, as these parts are concealed and it is not necessary to make them of expensive leather. The material of the envelope however, and 35 that portion of the papers section exposed to sight will ordinarily be made of the same material used in the construction of brief bags and other luggage, either leather or leather substitute.

Referring to the slight modification shown 40 in Figure 4, the numeral 18, designates a peripheral flange, which is attached to the part 19, which serves the same purpose as the part 6, in the main figures. In such construction the part 19 may preferably be made of thinner 45 material than the corresponding part 6, rigidity being given to the rear wall of the last pocket by reason of the permanent attachment of the flange 18, and its extension around the periphery of the part 19.

While in the bag illustrated the deeper portion of the box-like member is shown as having the papers section or pocket portion secured to it, obviously the box-like member 50 may be reversed and the cover portion of said member be attached to the pockets and the deeper portion secured to the envelope.

Having thus described the invention, what is claimed as new, is:

65 1. A brief case having an expansible

pocket, the rear wall of which is made rigid by the permanent attachment of a stiff box-like member, said pocket portion being open at the top edge, and an envelope member attached to the outer portion of the box-like member, and foldable over both sections.

2. A brief case including a pocket portion, a stiff box-like member permanently secured to the pocket portion and forming a rigid rear wall therefor, said pocket portion being 75 open at its upper edge, and an envelope member secured to the lower portion of the box-like member at the pocket portion and extending around the box-like member and over the opening of the pocket portion to enclose the box-like member and cover the pocket opening.

3. A brief case including a pocket portion, a stiff box-like member permanently secured to the pocket portion and forming a 85 rigid rear wall therefor, said box-like member including a cover arranged to swing at one edge toward and from the pocket portion to close and open the box-like member, said pocket portion being open at its upper edge, 90 and an envelope member secured to the lower portion of the box-like member at the pocket portion and extending around the box-like member and over the opening of the pocket portion to enclose the box-like member and 95 cover the pocket opening.

4. A brief case including a pocket portion, a stiff box-like member permanently secured to the pocket portion and forming a rigid rear wall therefor, said pocket portion being 100 open at its upper edge, an envelope member secured to the lower portion of the box-like member at the pocket portion and extending around the box-like member and over the opening of the pocket portion to enclose the box-like member and cover the pocket opening, and means to secure the free edge of the envelope member to the front of the pocket portion.

5. A brief case including a pocket portion, 110 a stiff box-like member permanently secured to the pocket portion and forming a rigid rear wall therefor, said box-like member including a cover arranged to swing at one edge toward and from the pocket portion to close 115 and open the box-like member, said pocket portion being open at its upper edge, an envelope member secured to the lower portion of the box-like member at the pocket portion and extending around the box-like member and over the opening of the pocket portion to enclose the box-like member and cover the pocket opening, and means to secure the free edge of the envelope member to the front of the pocket portion.

6. A brief case including a pocket portion, a stiff box-like member permanently secured to the pocket portion and forming a rigid rear wall therefor, said pocket portion being 120 open at its upper edge, said box-like mem-

- ber including a main portion and a cover hinged to said main portion at its lower edge, and an envelope member secured to the box-like member adjacent its lower edge and extending around the bottom, side and top of the box-like member and over the open edge of the pocket portion to close the latter. 5
7. A brief case including a pocket portion, a stiff box-like member permanently secured 10 to the pocket portion and forming a rigid rear wall therefor, said pocket portion being open at its upper edge, said box-like member including a main portion and a cover hinged to said main portion at its lower 15 edge, an envelope member secured to the box-like member adjacent its lower edge and extending around the bottom, side and top of the box-like member and over the open edge of the pocket portion to close the latter, and means to secure the free edge of the 20 envelope member to the front of the pocket portion.
8. A brief case including a pocket provided papers section having expandible edge 25 portions, a stiff box-like member forming an apparel section and permanently secured to the papers section to stiffen the same against bodily flexure, said apparel section including hinged elements closing one against 30 the other, an envelope member secured to the outermost of said elements and folding over both sections.
9. A brief case including an expandible papers section having associated therewith an 35 apparel section, comprising a shallow, rigid, box-like member adapted, in addition to serving as an apparel container, to brace the papers section against bodily flexure and a flap attached to the apparel section, and adapted, when the case is closed, to overlap both sections to form a closure for the papers section and to permit access to the apparel section only when said flap is in open position. 40
- 45 10. A brief case including an expandible pocket section having edgewise openings, a box-like member associated therewith adapted to serve as an apparel section and to brace the pocket section against bodily flexure, a flap secured to the apparel section and adapted to overlap both sections and form a clo-

sure for the pocket section and permit access to said apparel section only when said flap is open.

11. A brief case including an expandible 55 pocket section having edgewise openings, a box-like member associated therewith and adapted to serve as an apparel section and to brace the pocket section against bodily flexure, an envelope enveloping the box-like member and having one edge secured between said member and pocket section and the other terminating in a flap adapted to overlap the pocket section and form a closure therefor. 60

12. A brief case including an expandible 65 papers section having edgewise openings, there being permanently associated with said section an apparel section comprising a shallow boxlike member opening flatwise, said member in addition to serving as an apparel 70 container being adapted to brace the papers section against bodily flexure and a flap attached to the apparel section, and adapted, when the case is closed, to overlap both sections to form a closure for the papers section 75 and permit access to the apparel section only when the flap is open.

13. A brief case including an expandible 80 pocket section having edgewise openings, a boxlike member permanently associated therewith and opening flatwise, said member being adapted to serve as an apparel section and to brace the pocket section against bodily flexure, a flap secured to the apparel section and adapted to overlap both of the 85 sections to form a closure for the pocket section and permit access to the apparel section only when the flap is open.

14. A brief case including an expandible 90 pocket section having edgewise openings, a boxlike member associated therewith and opening flatwise, said member being adapted to serve as an apparel section and to brace the pocket section against bodily flexure, an envelope enveloping the boxlike member and having one edge secured between the member and the pocket section and the other terminating in a flap adapted to overlap the pocket section and form a closure therefor. 95

In testimony whereof he hereunto affixes 100 his signature.
